UNITED STATES PATENT OFFICE.

RAY L. STOKELY, OF FLORAL PARK, NEW YORK, ASSIGNOR TO WESTERN ELECTRIC COMPANY, INCORPORATED, OF NEW YORK, N. Y., A CORPORATION OF NEW YORK.

SEMITAUTOMATIC TELEPHONE SYSTEM.

Application filed July 1, 1921. Serial No. 481,747.

To all whom it may concern:

Be it known that I, RAY L. STOKELY, a citizen of the United States, residing at Floral Park, in the county of Nassau, State 5 of New York, have invented certain new and useful Improvements in Semiautomatic Telephone Systems, of which the following is a full, clear, concise, and exact description.

This invention relates to semi-automatic 10 telephone systems and more particularly to toll switching trunk circuits.

The object of the invention is to provide an improved arrangement for systems of this character.

15 One of the features of this invention is the provision of manual means for associating a calling device with a trunk leading to an automatic office, and means for automatically disconnecting the calling device 20 from the trunk as soon as the connector reaches the called line terminals whereby the calling device is immediately released for use in other calls.

Another feature is the provision of means 25 for automatically operating a supervisory signal before the operator as soon as the calling device is disconnected, this means being controlled by the condition of the called line, and operating the supervisory 30 signal in one manner if the line is idle, and in another manner if it is busy.

More specifically, a dialing cord circuit common to the toll position is provided; a number of toll connecting circuits is also 35 provided for each position. When the toll operator desires to set up a toll call to an automatic office she inserts the calling plugs of both of said circuits into a pair of jacks individual to the trunk. The 40 trunk is thus extended through contacts of a relay in the trunk to the dial in the cord circuit. The operator now turns the dial to set the switches at the automatic office. When the connector is set on the 45 called line the relay switches the trunk from the dial cord circuit to the connecting circuit. The line if idle causes the supervisory lamp in the connecting circuit to light, and the busy condition of the line causes the 50 signal to flash. The operator in the former case by depressing a key causes the connector to apply ringing current to the selected line. Upon the response of the 55 called party the lamp is extinguished.

Another feature is the provision of means

for automatically lighting a lamp in the cord circuit if any of the selectors encounters a busy trunk group.

Another feature is the provision of a pair of coin control keys associated with the cord 60 circuit, and if the call is to or from a pay station the operator after the response of the called party actuates the proper key to apply plus or minus current to the trunk from her position. A relay at the automatic office relays this current to the line to operate the coin box magnet.

A further feature is the provision of means for holding the connector on the line if it is busy, for causing the same to 70 seize such line as soon as it becomes idle, the seizure of the line causing the calling supervisory lamp to cease flashing and remain steadily lighted as a ringing signal to the toll operator, who thereupon actuates her ringing key to start the automatic ringing operation in the toll connector, the ringing current being cut off and the talking circuit completed upon the response of 75 the called party.

Other features will be pointed out in connection with the detailed description.

Referring to the drawings, Fig. 1 shows a combined dialing and coin cord circuit and also a part of a connecting circuit; Fig. 2 shows a toll switching trunk circuit; Fig. 3 shows an incoming selector; Fig. 4 shows a toll transmission selector repeater; Fig. 5 shows a toll connector; Fig. 6 shows 90 a toll rotary connector.

The invention will be more clearly understood from a detailed description of the operations involved in setting up a connection.

The toll operator having received the 95 number of the desired substation from the recording operator, or in any other suitable manner, touches the tip of her plug 100 to the tip of her jack 101, to select an idle trunk leading to the automatic office, and inserts the plug into the jack. Relays 102, 200 thereupon operate over the following circuit: free pole of battery, relays 102, 103, conductor 105, sleeves of the plug 105 and jack, relay 200, to ground! Relay 102 disconnects the busy test conductor and completes the tip conductor, and relay 200 prepares certain circuits which will be described latter. Relay 103 is marginal and 110 does not operate in this circuit, but only

when the plug 100 is inserted into a toll line. The operator now inserts the plug 106 of her dial cord into jack 107, which causes relays 108 and 201 to operate, the latter connecting the trunk conductors 202, 203 to the conductors 204, 205 leading to the operator's dial 109. Relay 201 removes the short circuit from about the right winding of relay 206, and this relay operates for a purpose which will appear.

Impulse relay 300 of the incoming selector at the automatic office now operates over the following circuit: free pole of battery, lower winding of relay 300, armature 308, and normal contact of relay 307, conductors 306, 203, armature 209, and alternate contact of relay 201, conductor 205, ring of the jack 107, ring of the plug 106, normal contact of key 120, conductor 121, relay 110, middle right armature and normal contact of relay 115, conductor 122, impulse contact 112 of the dial, conductor 123, outer right hand armature and normal contact of relay 115, normal contact of key 120, tip of the plug, tip of the jack, conductor 204, upper armature and alternate contact of relay 201, conductors 202, 305, armature 309, and normal contact of relay 307, upper winding of relay 300, normal contact of switch 304, to ground. Relays 300 and 110 operate in this circuit. Relay 110 operates slow relay 113 in a circuit including the inner right armature of relay 115, and relay 113 in attracting its inner right armature locks itself to ground at the armature and alternate contact of relay 108. The impulse relay 300 of the incoming selector in operating energizes the usual slow relay 301, which opens the circuit of release magnet 302, and prepares the circuit of vertical magnet 303 in the well-known manner. The operator now turns the dial to transmit the first digit of the desired number. Off-normal contact 114 on the dial operates relay 115 which locks through the armature and front contact of relay 108. At its middle armature relay 115 opens the original energizing circuit of relay 110, but this relay remains energized in a circuit including the left armature and front contact of slow relay 113. The dial restoring interrupts the loop including the impulse relay 300 and the relay 110. The vertical magnet 303 receives impulses from impulse relay 300 in the well-known manner and raises the selector to the desired level, which automatically hunts for an idle trunk leading to a toll transmission selector (Fig. 4). The operation of the incoming selector (Fig. 3), will not be described in detail, since it is of the standard type shown and described for example in Patent No. 1,377,225 issued May 10, 1921 to A. J. Seymour. Relay 113 in the dial cord being slow, does not release, as its circuit is intermittently opened by relay 110. If, however, the incoming selector

(Fig. 3), fails to find an idle trunk, it operates switch 304 on its eleventh step which opens the loop circuit including relays 300 and 110. This results in the deenergization of relay 110, for a period long enough to release slow relay 113, which at its outer right armature lights the all busy trunks lamp 116, whereupon the operator withdraws plugs 100 and 106, and waits and sets up the connection later.

Assuming however that the incoming selector (Fig. 3), finds an idle trunk, relay 307 operates and extends the trunk conductors 305 and 306 through to the toll selector (Fig. 4), whereupon the impulse relay 400 thereof operates over the following circuit: free pole of battery, left winding of relay 400, outer right armature and normal contact of relay 401, normal left contact of relay 402, lower left-hand winding of the repeating coil RC to the lower talking conductor, over the path traced to the dial cord, returning over the upper talking conductor through the upper left-hand winding of repeating coil RC, right normal contact of relay 402, inner right armature and normal contact of relay 401, right winding of relay 400, switch 404 to ground. The impulse relay of the toll transmission selector and the relay 110 are energized in this circuit, the latter maintaining the slow relay 113 energized to prevent the lighting of the all trunks busy lamp 116, and the former operating the usual slow relay 405 to interpose a break in the circuit of the release magnet 420 and prepare the circuit of the vertical magnet 407. Relay 405 in attracting its inner right armature, grounds the release wire 406 leading back to the incoming selector to hold up the relay 307 after the slow relay 301 releases in the well-known manner. This ground also causes the seized toll transmission selector to test busy to other incoming selectors. The operator now turns the dial for the next digit and upon the restoration of the dial, relay 400 transmits impulses to the vertical magnet 407 to raise the toll selector to the desired level. The slow relay 412 in series with the vertical magnet 407 operates a relay 421, this circuit including off-normal contact 422 and the outer right armature and alternate contact of relay 405. Relay 421 in attracting its left armature, locks itself over a circuit including the armature and normal contact of magnet 423, and the inner armature and the normal contact of slow relay 424. Relay 412 also operates a relay 411, this circuit also including the outer right armature and normal contact of relay 405. This relay locks up in a circuit including its armature 413 and the outer right armature of relay 405. When slow relay 412 releases upon the termination of the vertical impulses the rotary magnet 423 is operated over a circuit in-

cluding the right armature of relay 421, normal contact of relay 412, and outer right armature and normal contact of relay 405. The rotary magnet steps the brushes onto the first trunk, and at the end of its stroke opens the locking circuit of relay 421 which releases, opening the circuit of the rotary magnet in the well-known manner. If the first trunk is busy, its test multiple 425 is 10 grounded and relay 421 again operates over a circuit including the off normal switch 422, armature and normal contact of the rotary magnet, conductor 426, armature 417, outer right armature of relay 424, conductor 416, 15 to the grounded test multiple 425. Relay 421 again closes the circuit of the rotary magnet and locks up in the circuit previously traced. The rotary magnet steps the brushes to the next trunk.

20 This interaction between the relay 421 and magnet 423 continues until an ungrounded test multiple is reached, whereupon the relay 408 operates over a circuit including relay 421, switch 422, normal contact of magnet 423, conductor 426, relay 408, to ground at the outer right armature and front contact of relay 405. Relay 408 extends the conductors 409, 410 to the impulse relay 500 of the toll connector which immediately 25 operates over the following circuit: free pole of battery, right winding of relay 500, conductor 512, armature 513, and normal contact of relay 505, lower talking conductors (Figs. 5 and 4), lower right winding 30 of repeating coil RC, left armature and front contact of relay 411, left winding of relay 418, upper right winding of the repeating coil RC, upper talking conductors (Figs. 4 and 5), armature 514, and normal contact of relay 505, left winding of relay 500, to ground. Relay 411 is not released 35 due to the seizure of the toll connector since contact 414 is a make-before-break contact. Relay 411 is thus held up over the following 40 circuit: free pole of battery, relay 411, armature 413, and its front contact, contact 414, control lead 415, conductor 504, armature 515, and normal contact of relay 505, sleeve conductors 506, 416, armature 417, and alternate contact of relay 408 to ground at 45 the outer right armature of relay 405. When the loop circuit was closed including the left winding of relay 418, a circuit was simultaneously closed through the right winding of said relay at the lowermost armature and front contact of relay 408. These windings neutralize each other and consequently relay 418 remains inert. Relay 500 operates slow relay 501 over a circuit including the upper winding of said relay and the lowermost armature and back contact of relay 505. Relay 501 in attracting its uppermost armature locks itself to the sleeve wire 506 by way of the armature 515 of the relay 505, and connects the ver-

tical magnet 502 to the back contact of the impulse relay 500, and opens the circuit of release magnet 503. The operator now turns the dial for the tens digit, and the relay 400, the circuit of which has been previously 70 traced, repeats the impulses to relay 500 which transmits impulses to the vertical magnet 502 to raise the connector to the desired level. The usual slow relay 507 is in series with the vertical magnet. 75 The first impulse for the vertical magnet passes by way of contact 517 of the off-normal switch 516, and the succeeding impulses pass by way of contact 518, and the armature and front contact of slow relay 507. 80

Upon the cessation of the vertical impulses, relay 507 releases, connecting the rotary magnet 508 to the back contact of the impulse relay 500. The operator now turns the dial for the units digit to rotate the brushes into contact with the desired line. The slow relay 509 in series with the rotary magnet upon its operation energizes slow relay 510 from the ground on the sleeve wire 506. Relay 509 in attracting its left armature operates relay 519 which locks up to the sleeve wire 506. When relay 509 releases, its right armature connects relay 511 over the inner right armature of relay 510 which if the selected line is busy, locks up to the ground at its test multiple. Relay 511 operates from this ground and reverses the direction of the current flow in the trunk leading back to the relay 418 in the toll transmission selector (Fig. 4), which causes the polarized relay 418 to operate. Relay 418 at its armature 419 operates relay 402 from the ground at the lowermost armature of relay 408. Relay 402 reverses the direction of current flow in the trunk leading back to the dial and coin cord circuit. This causes the polarized relay 111 to operate, and removes the short-circuit from about relay 117, whereupon the marginal relay 201 releases, disconnecting the trunk 202, 203 from the dial cord and extending it to the connecting cord. Relay 437 being marginal does not operate 110 at this time. Relay 201 in releasing, locks up relay 206 and provides a circuit for relay 208 which operates and closes a break in the ring conductor. The supervisory lamp 119 in the connecting circuit now flashes to indicate the busy condition of the desired line. This is brought about in the following manner: Relay 418 in attracting its innermost 115 left armature, connects an interrupter 427 to the lower winding of relay 428, the circuit being as follows: innermost armature of relay 418, lower winding of the relay 428, armature 429, front contact of relay 411 to ground at the left armature and front contact of relay 400. Relay 428 in intermittently attracting its armature 430 applies a 120

ground to conductor 431 which intermittently shunts out the supervisory relay 118 in the connecting cord causing the flashing of the lamp 119. The operator thus knows that the line is busy, and attends to her other duties. As soon as the line becomes idle, the ground is removed from its test multiple, which releases the relay 510. Relay 510 in releasing its outer right armature, grounds the test multiples, and in releasing its inner right armature deenergizes relay 511. Relay 510 in retracting its left armature, operates relay 505 from the ground on the sleeve wire 506. Relay 505 in attracting its armature 515 opens the circuit previously traced for the relay 411. Relay 411 in retracting its armature 429, opens the circuit including the interrupter 427 and relay 428, relay 428 remaining inert, causing the supervisory lamp 119 to remain steadily lighted. This serves as a ringing signal to the toll operator, who thereupon depresses her ringing key RK to impress ringing current on the trunk to operate relay 432 over the trunk conductors in series. Relay 432 in attracting its armature operates relay 428 over a circuit including the armature 433, lower winding of relay 428, armature 429 of relay 411, and armature 434 of relay 418. Relay 428 in attracting its armature 430 opens the circuit previously traced for the relay 501 which releases and applies ringing current to the selected line. Upon the response of the called party, relay 501 operates in the well-known manner and again locks up to the grounded control lead 504 and completes the talking circuit. Relay 435 now operates in series with the called line over the following circuit: free pole of battery, left winding of relay 435, relay 436, left-hand armature and back contact of relay 411, lower right-hand windings of the repeating coil, lower talking conductor, returning over the inner right armature of relay 411 to ground at the right winding of relay 435. Relay 436 operates relay 401 which in attracting its right armatures removes battery from the trunk conductors leading back to the connecting cord, and the outer right armature closing a bridge to hold relay 400 operated. The removal of battery from the trunk leading to the connecting cord, releases the supervisory relay 118 which extinguishes the lamp 119 indicating to the operator that the called party has responded. Talking current is fed to the calling line over the windings of the repeating coil at the distant office (not shown).

If the substation A to which connection has been made is a pay station the operator will communicate with the called party and inform him of the coins to be deposited. She checks this by the sound from the gongs which the coins strike in passing through the chutes of the coin box in the

well-known manner. The operator now reinserts the plug 106 into the jack 107. Since relay 115 does not operate until the dial is moved off normal, relay 111 is short circuited and does not operate, consequently relay 117 does not operate. Relay 201 however, operates to extend the tip and ring of the trunk to the cord circuit. The operator then actuates key 120, which connects a 110 volt source of current to the ring of the trunk to operate relay 437 in the transmission selector. The circuit for relay 437 is as follows: free pole of battery, contact of key 120, ring of the plug 106, ring of the jack 107, armature 209 of relay 201, ring conductors 203, 306, armature 308, alternate contact of relay 307, ring conductors (Figs. 3 and 4), lower left winding of the repeating coil RC, conductor 438, left armature and alternate contact of relay 402, relay 437 and its normal contact, conductor 439, inner right armature and front contact of relay 401, conductor 440, right armature and front contact of relay 402, conductor 403, upper left winding of the repeating coil RC, upper talking conductor (Figs. 4, 3 and 2), upper armature and alternate contact of relay 201, conductor 204, tips of the jack and plug, contact of key 120, conductors 124, 125, normal contact of key 126, conductor 127, normal contact of key 128 to ground. Relay 437 in attracting its armature 441 locks itself to ground, and in attracting its armature 442 transfers the tip of the trunk from its normal connections to the tip and ring of the called line. If the called subscriber's receiver is on the switchhook, the operating circuit for relay 437 leads through the right winding of relay 400 to ground. Key 120 while actuated remains in its actuated position until released by the operator. The operator now depresses one of the coin keys 126 or 128, which will impress plus or minus 110 volts upon the tip of the trunk. Relay 437 being operated, permits this current to flow over the talking conductors in parallel to ground, through the polarized magnet in the coin box. This coin box may be of the type shown and described in Patent No. 1,043,219, issued Nov. 5, 1912 to O. F. Forsberg. The deposit of the coin or coins connects the polarized magnet to ground. If this ground is present, relay 130 in the cord circuit will operate, lighting the lamp 131 to indicate to the operator the condition of the circuit; that is to say, if no coins have been deposited, relay 130 will not operate and the lamp 131 will not glow. The release of the coin key in releasing the magnet causes the magnet to disconnect itself from ground, thus opening the circuit of relay 130, which extinguishes the lamp 131. The operator now releases the key 120, whereupon the relay 437 restores and completes

the talking circuit in the transmission selector.

The operator now withdraws the plug 106 whereupon the relay 201 releases, completing the talking circuit at the trunk (Fig. 2). The subscriber at substation A by actuating his receiver hook causes relay 436 to intermittently operate relay 401, which applies and removes battery from the trunk, 10 thus intermittently operating the relay 118 to flash the lamp 119. Inasmuch as relay 400 is held up either through the bridge including the resistance when the receiver hook is up, or over the trunk leading back 15 to the connecting cord when the receiver hook is down, relay 405 is maintained energized to prevent release.

When the party at substation A restores the receiver, relay 436 releases, releasing relay 401 which replaces battery on the trunk operating relay 118 to light the lamp 119. When the operator desires to break down the connection she withdraws the plug 100 from jack 101 which places relay 210 across 25 the trunk by the release of the left armature of relay 200. Thus, and if the subscriber's receiver is still off the hook, there will be no battery on the trunk, and relay 210 will not operate. Relay 208 remains 30 operated to apply battery through its outer armature and the inner right armature of relay 200, to the sleeve of the jack 101 to cause this trunk to test busy. When the subscriber hangs up his receiver, battery is 35 applied to the trunk as described, which causes relay 210 to operate to open the locking circuit of relay 208, whereupon relay 208 releases, opening the loop circuit including relay 210 which releases relay 400, 40 and since the relay 401 is at this time inert due to the subscriber having replaced his receiver, relay 405 is released. Relay 405 at its inner right armature removes ground from the sleeve wire 406 to deenergize 45 switching relay 307. This relay at its uppermost armature closes the circuit of release magnet 302 to restore the incoming selector. The retraction of the left armatures of relays 405 and 400 operates the release magnet 420 of 50 the transmission selector. The release of the transmission selector releases relays 505, 501 and 519. Release of the relays 505 and 501 completes the circuit for the release magnet 503 of the connector from free pole of battery, magnet 503, off-normal switch 516, lowermost armature and normal contact of relay 501, left armature and back contact of relay 500, lowermost armature and normal contact of relay 505 to ground.

60 Referring now to Fig. 6, it shows a toll rotary connector, that is to say, a connector wherein private branch exchange lines terminate. This circuit is so arranged that if all the trunks corresponding to the called number are busy, the switch will wait in

front of the trunk group and cause the supervisory lamp 119 to flash. When one of these trunks becomes idle the switch will move along the bank and seize this trunk automatically, and upon the seizure of such 70 trunk will cause the lamp 119 to remain steadily lighted as a ringing signal. The operator will then depress her ringing key and cause a ringing operation to start. The remaining operations are the same as those 75 traced in connection with the toll connector. The operations involved in raising the toll rotary connector to the desired level are exactly the same as those described in the case of the toll connector, the relay 600 transmitting impulses to the vertical magnet 602 and the relay 607 on the termination of these 80 impulses closing the circuit of rotary magnet 608. The rotary magnet then in response to impulses from the impulse relay 85 600 rotates the brushes to the first trunk. Slow relay 609 energizes upon the first rotary impulse and operates relays 610, 620, and 619. Relay 619 locks up to the sleeve wire 606. If all trunks are busy, a series 90 of chain relays 621, 622 etc. extends the ground on the last test multiples 623, 624 to the multiple 626. Relay 610 at its inner left armature locks up to ground at multiple 625, and at its inner right armature holds relay 95 620 operated from the ground on test multiple 626 to prevent the switch from stepping. Relay 610 at its outer right armature operates relay 611 over the following circuit, 100 free pole of battery, relay 611, left armature and front contact of relay 620, outer armature and front contact of relay 610, lower armature and front contact of relay 619, left armature of relay 609 to ground on the sleeve wire 606. Relay 611 reverses the direction of current flow in the trunk leading back to the relay 418, just as in the case of a busy ordinary line, which relay 418 in operating, connects the interrupter in circuit with the relay 428, which intermittently applies ground in shunt of the supervisory relay 118 to flash the lamp 119 before the toll operator. As soon as one of the trunks becomes idle a chain relay releases disconnecting the ground from test multiple 626, 105 which causes the release of relay 620. If this idle trunk is the one upon which the switch is resting the removal of the ground from its test multiple 625 releases the slow relay 610, whereupon the relay 605 operates 110 over the following circuits: free pole of battery, relay 605, outer right armature of relay 610, lower armature and front contact of relay 619, left armature and back contact of relay 609 to ground on the sleeve wire 606. Relay 605 in attracting its uppermost armature releases relay 411 of the toll transmission selector which in retracting its outermost right armature holds relay 402 115 operated independently of relay 418, and in 120

125

130

releasing its armature 429 opens the circuit of interrupter 427 and relay 428, whereupon the lamp 119 remains steadily lighted to serve as a ringing signal to the operator.

- 5 If, on the other hand, the idle trunk was an intermediate trunk, the ground on the test multiple 625 is transmitted by way of the right armature and back contact of relay 620 to the relay 627, relay 610 remaining 10 locked up on this ground over its left winding. Relay 627 in attracting its left armature locks up over the back contact of the rotary magnet 608, and at its right armature transmits an impulse to this magnet. The 15 rotary magnet at the end of its stroke opens the locking circuit of relay 627, which in releasing its right armature, opens the circuit of the rotary magnet. This interaction continues, and the rotary magnet steps 20 the switch around until it reaches the ungrounded test multiple 628, whereupon relay 610 releases, operating relay 605, with the results described. The operator in response to the lighting of the lamp operates 25 her ringing key, which energizes relay 432 to operate relay 428, which in attracting its armature 430, releases relay 601 to start the automatic ringing operation. The remaining operations are the same as those described in the case of the toll connector.

What is claimed is:

1. In a telephone system, a trunk terminating at one end in a pair of jacks and at the other end in an automatic switch, other automatic switches, a cord circuit and a connecting circuit for connection with said jacks respectively, a dial associated with said cord circuit for setting said switches, means for automatically disconnecting said trunk conductors from the cord circuit and connecting the same to the connecting circuit upon the selection of the called line, and means for maintaining the setting of the switches after said transfer from the cord circuit to the connecting circuit has taken place.

2. In a telephone system, a trunk terminating at one end in a pair of jacks and at the other end in an automatic switch, other 50 automatic switches, a cord circuit and a connecting circuit for connection with said jacks respectively, a dial associated with said cord circuit for setting said switches, means for automatically disconnecting said trunk conductors from the cord circuit and connecting the same to the connecting circuit upon the selection of the called line, means for maintaining the setting of the switches if the called line is in busy condition, a 55 supervisory signal, a supervisory relay in the connecting circuit, and means controlled by the idle condition of the called line for operating said relay to control said signal.

3. In a telephone system, a trunk terminating at one end in a pair of jacks and at the

other end in an automatic switch, other automatic switches, a cord circuit and a connecting circuit for connection with said jacks respectively, a dial associated with said cord circuit for setting said switches, means for automatically disconnecting said trunk conductors from the cord circuit and connecting the same to the connecting circuit upon the selection of the called line, a supervisory signal, a supervisory relay in the connecting circuit, means actuated by the busy condition of the called line for causing said supervisory relay to operate said signal in one manner, means actuated by the idle condition of the called line for causing said supervisory relay to operate said signal in another manner and means for maintaining the setting of the switches regardless of the busy or idle condition of the called line.

4. In a telephone system, a trunk terminating at one end in a pair of jacks and at the other end in an automatic switch, other automatic switches, a cord circuit and a connecting circuit for connection with said jacks respectively, a dial associated with said cord circuit for setting said switches, means for automatically disconnecting said trunk conductors from the cord circuit and connecting the same to the connecting circuit upon the selection of the called line, a supervisory lamp, a supervisory relay in the connecting circuit, means actuated by the busy condition of the called line for causing said supervisory relay to flash said lamp, and means actuated by the idle condition of the called line for causing said supervisory relay to steadily light said lamp.

5. In a telephone system, a trunk terminating at one end in a pair of jacks and at the other end in an automatic switch, other automatic switches, a cord circuit and a connecting circuit for connection with said jacks respectively, a dial associated with said cord circuit for setting said switches, means for automatically disconnecting said trunk conductors from the cord circuit and connecting the same to the connecting circuit upon the selection of the called line, a supervisory lamp, a supervisory relay in the connecting circuit, means actuated by the busy condition of the called line for causing said supervisory relay to flash said lamp, means actuated by the idle condition of the called line for causing said supervisory relay to steadily light said lamp, and manual means in said connecting circuit adapted when actuated to cause ringing current to be applied to the called line from said connector.

6. In a telephone exchange system, a toll board, an automatic office, a trunk having two conductors only terminating at said board in a pair of jacks, and at said automatic office in a selector, other automatic switches, a cord circuit and a connecting circuit at said toll board for connection with the jacks respec-

tively, a dial associated with said cord circuit for setting said switches, means for automatically disconnecting said trunk conductors from said cord circuit and connecting the same to the connecting circuit upon the selection of the called line, a supervisory lamp in said connecting circuit, a supervisory relay therein, means actuated by the busy condition of the selected line for causing said relay to flash said lamp, and means controlled by the idle condition of the selected line for causing said relay to steadily light said lamp.

7. In telephone exchange system, a toll board, an automatic office, a trunk having two conductors only terminating at said board in a pair of jacks, and at said automatic office in a selector, other automatic switches, a cord circuit and a connecting circuit at said toll board for connection with the jacks respectively, a dial associated with said cord circuit for setting said switches, means for automatically disconnecting said trunk conductors from said cord circuit and connecting the same to the connecting circuit upon the selection of the called line, a supervisory lamp in said connecting circuit, a supervisory relay therein, means actuated by the busy condition of the selected line for causing said relay to flash said lamp, and means controlled by the idle condition of the selected line for causing said relay to steadily light said lamp, and a key actuated by the toll operator to cause ringing current to be applied to the selected line.

8. In a telephone system, the combination with an operator's position, a trunk terminating thereat in a jack and at its other end in a selector, groups of trunks terminating in said selector, a cord circuit at said position, a lamp associated with said cord circuit, a slow relay, a dial for said cord circuit, a fast relay at said cord circuit, a loop circuit including said dial, said fast relay and the impulse relay of the selector, a circuit for said slow relay, closed at a front contact of said fast relay, a circuit for said lamp including a back contact of said slow relay, and means actuated by the selector in case all the trunks are busy for permanently opening said loop circuit, whereupon said fast relay releases said slow relay to light said lamp.

9. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited,

and a relay operated upon the selection of the desired line to remove the short-circuit from about said resistance to cause said relay to release and connect said trunk conductors to said connecting circuit.

10. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited, a relay operated upon the selection of the desired line to remove the short-circuit from about said resistance to cause said relay to release and connect said trunk conductors to said connecting circuit, a supervisory relay in said connecting circuit, a supervisory lamp, and means controlled by the busy condition of the desired line for causing said relay to flash said lamp.

11. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited, a relay operated upon the selection of the desired line to remove the short-circuit from about said resistance to cause said relay to release and connect said trunk conductors to said connecting circuit, a supervisory relay in said connecting circuit, a supervisory lamp, means controlled by the busy condition of the desired line for causing said relay to flash said lamp, and means controlled by the idle condition of the selected line for causing said relay to steadily light said lamp.

12. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited, a relay operated upon the selection of the desired line to remove the short-circuit from about said resistance to cause said relay to release and connect said trunk conductors to said connecting circuit, a supervisory relay in said connecting circuit,

cuit, a supervisory lamp, means controlled by the busy condition of the desired line for causing said relay to flash said lamp, means controlled by the idle condition of the selected line for causing said relay to steadily light said lamp; means actuated by the operator to cause ringing current to be applied to the selected line, and means actuated by the response of the called party for disconnecting said ringing current and extinguishing said lamp.

13. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited, a relay operated upon the selection of the desired line to remove the short-circuit from about said resistance to cause said relay to release and connect said trunk conductors to said connecting circuit, a supervisory relay in said connecting circuit, a supervisory lamp, means controlled by the busy condition of the desired line for causing said relay to flash said lamp, means controlled by the idle condition of the selected line for causing said relay to steadily light said lamp, means actuated by the operator to cause ringing current to be applied to the selected line, means actuated by the response of the called party for disconnecting said ringing current and extinguishing said lamp and means controlled by replacement of the receiver by the called party for lighting said lamp.

14. In a telephone system, an operator's position, a trunk terminating thereat in a jack and at its other end in a selector, other automatic switches, a cord circuit and a connecting circuit for connection with said jacks respectively, a dial associated with the cord circuit for setting said switches, a relay in the trunk operated upon the connection of the cord circuit to the trunk to connect the trunk conductors to the dial, a resistance in the cord circuit normally short-circuited, a polarized relay in said cord circuit controlling said short circuit, and means actuated by the selection of the called line for reversing the current flow through said relay to operate the same to remove said short circuit from about said resistance to cause said relay in the trunk to release and connect said trunk conductors to said connecting circuit.

15. In a telephone system, a trunk terminating at one end in a manual switch and at its other end in an automatic switch, other automatic switches, a cord circuit ter-

minating in a manual switch for connection with the manual switch of the trunk, a connecting circuit for association with said trunk, a calling device associated with the said cord circuit, means for automatically disconnecting the trunk conductors from the manual switch of the trunk and for connecting the trunk conductors to said connecting circuit upon the selection of the desired line, and means for maintaining the called line associated with said trunk after the transfer of the trunk from the cord circuit to the connecting circuit.

16. In a semi-automatic telephone system, telephone lines, a cord circuit, trunk lines accessible thereto, a calling device adapted to be associated with said trunk circuit by means of said cord circuit, a connecting circuit, and means controlled by the selection of the called line for automatically disconnecting said calling device from said trunk circuit, and for connecting said trunk circuit to said connecting circuit and for maintaining the called line connected to said trunk after the transfer from the cord circuit to the connecting circuit has taken place.

17. In a semi-automatic telephone system, telephone lines, a cord circuit, a trunk circuit, a dial, manual means for associating said dial with said trunk, automatic switches controlled by said dial for extending the trunk circuit to a telephone line, a connecting circuit having a supervisory signal, means controlled by the idle condition of the called line for automatically disconnecting said dial from said trunk and operating said supervisory signal and means controlled by the busy condition of the connected telephone line for automatically disconnecting said dial and maintaining the telephone line connected to said trunk.

18. In a semi-automatic telephone system, telephone lines, a cord circuit, a trunk circuit, a dial, manual means for associating said dial with said trunk, automatic switches controlled by said dial for connecting a trunk circuit to a telephone line, a connecting circuit having a supervisory lamp, means controlled by the busy condition of the called line for automatically disconnecting said dial from said trunk and flashing said lamp and maintaining the called line connected to said trunk.

19. In a telephone system, a toll trunk terminating at one end in a manual switch and at its other end in an automatic switch, other automatic switches including a connector, private branch exchange trunks terminating in said connector, a cord circuit terminating in a manual switch for connection to the manual switch of the trunk, a connecting circuit, a dial associated with said cord circuit, and means for automatically disconnecting the trunk conductors

from the manual switch of the trunk and for connecting the trunk conductors to said connecting circuit upon the selection of the first private branch exchange trunks.

- 5 . 20. In a telephone system, a trunk terminating at one end in a manual switch and at its other end in an automatic switch, other automatic switches including a connector, private branch exchange trunks terminating 45 in said connector, a cord circuit terminating in a manual switch for connection to the manual switch of the trunk, a connecting circuit, a dial associated with said cord circuit, means for automatically disconnecting the trunk conductors from the manual switch of the trunk and for connecting the trunk conductors to said connecting circuit upon the selection of the first private branch exchange trunks, a supervisory lamp in said 50 connecting circuit means whereby said connector automatically tests said private branch exchange trunks, and means operated upon the selection of an idle private branch exchange trunk for lighting said supervisory 55 lamp.
21. In a telephone system, a trunk terminating at one end in a manual switch and at its other end in an automatic switch, other automatic switches including a connector, private branch exchange trunks terminating 60 in said connector, a cord circuit terminating in a manual switch for connection to the manual switch of the trunk, a connecting circuit, a dial associated with said cord circuit for setting said switches means for automatically disconnecting the trunk conductors from the manual switch of the trunk and for connecting the trunk conductors to said connecting circuit upon the selection of the first private branch exchange trunk a supervisory lamp in said connecting circuit, means 65 whereby said connector tests said private branch exchange trunks, means operated upon the selection of an idle private branch exchange trunk for lighting said supervisory lamp, means automatically operated if all 70 the private branch exchange trunks are busy for holding the connector set on the first trunk and for flashing said supervisory lamp, and means operated when one of the private branch exchange trunks becomes 75 idle for causing the connector to select and seize the same and for steadily lighting said lamp.
- 30

- 40

connecting circuit, means whereby said connector automatically tests said private branch exchange trunks, means operated upon the selection of an idle private branch exchange trunk for lighting said supervisory 45 lamp, and means automatically operated if all the private branch exchange trunks are busy for flashing said supervisory lamp.

22. In a telephone system, a trunk terminating at one end in a manual switch and at its other end in an automatic switch, other automatic switches including a connector, private branch exchange trunks terminating 55 in said connector, a cord circuit terminating in a manual switch for connection to the manual switch of the trunk, a connecting circuit, a dial associated with said cord circuit for setting said switches means for automatically disconnecting the trunk conductors from the manual switch of the trunk and for connecting the trunk conductors to said connecting circuit upon the selection of the first private branch exchange trunk a supervisory lamp in said connecting circuit, means 60 whereby said connector tests said private branch exchange trunks, means operated upon the selection of an idle private branch exchange trunk for lighting said supervisory lamp, means automatically operated if all 65 the private branch exchange trunks are busy for holding the connector set on the first trunk and for flashing said supervisory lamp, and means operated when one of the private branch exchange trunks becomes 70 idle for causing the connector to select and seize the same and for steadily lighting said lamp.

In witness whereof, I hereunto subscribe my name this 28th day of June A. D., 1921.

RAY L. STOKELY.
